UNITED STATES PATENT OFFICE.

ASA E. LANDON, OF CANTON, PENNSYLVANIA.

FILE.

No. 832,549.

Specification of Letters Patent.

Patented Oct. 2, 1906.

Application filed January 16, 1906. Serial No. 296,383.

To all whom it may concern:

Be it known that I, ASA E. LANDON, a citizen of the United States, residing at Canton, in the county of Bradford and State of Pennsylvania, have invented certain new and useful Improvements in Files, of which the following is a specification.

This invention relates to improvements in filing devices intended more particularly for the reception and preservation of the sales-slips used by merchants in transacting business with their credit customers; and the object of the invention is to provide certain improvements in the file described in Letters Patent No. 800,858, granted to myself and Warren F. Beck and bearing date October 3, 1905. In the file as described in said Letters Patent the compartments are made shorter than the slips which are to be filed therein, thereby exposing to view one entire end of the slips, whereon are written the customer's name and a statement of his account, these slips when inserted in the file in their proper compartments constituting an alphabetically-arranged ledger. As the customers' names are written upon the slips in pencil by various clerks when taking the customers' orders, these names as they appear in the file are in the handwriting of different persons, and by reason of the hurried manner in which they are written are more or less illegible. It is therefore desirable that each customer's compartment shall be provided with some means for displaying in uniform and clear lettering the customer's name, and, if desired, his house or business address or other index matter. Another undesirable feature in the exposing of the entire end portion of the slips is the liability of the slips to become roughed up in going over the ledger, thereby causing them to present a mussed appearance, and also rendering them liable to become torn, since they are held down only in the center, where the retaining-bar presses upon them. To overcome these objectionable features, each compartment in this improved file will be provided with a labeling or index member, which may be formed by or attached to the division flaps or partitions or inserted separately in the compartments above the sales-slips. These index members will extend to the top of the sales-slips, so as to cover and conceal the slips except as to that portion upon which is written the statement of the customer's account.

A further object is to provide an arrangement of the retaining bar or bail whereby springs will be dispensed with and positive pressure will be applied to the bars to cause them to bear upon the compartments, said bars being arranged to bear upon the index members of the compartments to press them upon the underlying slips.

The above objects are attained by constructing the file in the manner illustrated in the accompanying drawings, in which—

Figure 1 represents a plan view of one leaf of a filing-case embodying these improvements with a second leaf hinged thereto at the right-hand side and shown in longitudinal section; Fig. 2, a transverse section of the same on the line *xx*; Fig. 3, a detail on larger scale to illustrate the manner of locking the bail in its retaining position and swinging it away from the compartments to clear the file contents. Fig. 4 represents a customary form of sales-slip intended for use in connection with this file; Fig. 5, an individual name-card and cash-payment account adapted to be used as the index member in connection with this file; Fig. 6, a plan view of one of the individual compartment flaps or partitions with the index member formed integrally therewith; Fig. 7, a detail showing a sectional view of a modified form of the compartment flaps or partitions, wherein clamps are provided for the attachment thereto of separate index members in the form of cards narrower than the compartments and having the name or other index matter displayed thereon, as in the lower right-hand compartment in Fig. 1.

Like letters of reference designate like parts in the several views.

The file as herein illustrated consists of leaves A A, hinged together, each leaf comprising a shallow rectangular tray or receptacle formed of wood or other material of suitable lightness and strength. Running longitudinally through the center of each leaf is a channel-piece C, composed, preferably, of sheet metal bent into the form illustrated. In the longitudinal divisions formed by said strip are arranged a series of compartments formed by the overlapping flaps B, each flap in a series projecting a short distance beyond the next overlying flap and forming a compartment in which may be placed the sales-slips belonging to any given customer as they are made out from time to time in the

course of business transactions. These flaps are preferably formed from cartridge-paper and applied to the receptacles in the manner described in the Letters Patent aforesaid.

5 The retaining-bars D are of stiff wire bent in the form of bails and hinged at one end to the leaves A by means of outturned projections E, slipped into corresponding sockets provided at one end of the leaves. At the 10 other end these bails are provided with hooked portions F, which pass through staples or eyes G, attached to the end or to the bottom of the receptacle. These staples or eyes are positioned, preferably, directly opposite the hinge projections E, and the hooked arms of the bails are of such a length that when a bail is thrown over upon the file compartments and the hooked portion pushed through the eye to a greater or less 15 extent, as indicated by the broken lines in Fig. 3, pressure will be exerted upon the bail to press it upon the compartments. To form a bearing for the hooked end of the bails, the channel-pieces C will preferably have the 20 flanges at that end bent down upon the back of the receptacle, as shown at c, thus interposing a metal strip between the hooked end of the bails and the back of the receptacle. To throw a bail away from the compartments, 25 the hooked end is drawn out until the bend of the hook will swing around in the eye G, as shown in full lines in Fig. 3, after which the bail is thrown over into the channel C, as shown at the left-hand side of Figs. 1 and 2, 30 the return-bend of the bail-hook being of a length sufficient to prevent the bail from being freed from the eye G when laid over in this open position, as will be seen more clearly from an inspection of the left-hand bail in 35 Fig. 2. If desired, both ends of the bail may be provided with this hooked connection.

In the lower left-hand corner of the file in Fig. 1 the compartment flap or partition B is shown cut shorter than the sales-slips, as in 45 the aforesaid Letters Patent; but below the flap there is inserted an index member in the form of a card J of stiff paper or cardboard, as shown in full in Fig. 5, said card being of the same size as the slips and having a head 50 portion I provided where it projects above the flap B for the insertion of a customer's name and, if desired, his address or other index matter. This card has a corner cut out at H, so as to expose the items entered in the 55 upper right-hand corner of the sales-slips, and may be ruled off with lines and columns headed by the words "Date" and "Paid," wherein will be entered the payments made on account by the customer, together with the 60 date of payment. It then becomes a record of such payments on account, while the slips filed beneath give the record of the credit transactions, the uppermost slip showing through the cut-out corner the balance due 65 on the account at any time. Thus the up-

permost slip in the R. O. Dunn account where exposed shows that there was brought forward from the preceding slip a total charge of three dollars and ten cents, that the items charged on said uppermost slip amounted to 70 one dollar and fifty-five cents, and that the total account amounts to four dollars and sixty-five cents. If a payment in full of the 75 account is made, this item of four dollars and sixty-five cents, with date of payment, will be entered on the card J, as shown, and to remove the charge from the slips a cash-slip will be inserted, having entered in the exposed space the "\$4.65" as brought forward and underneath it the payment item of 80 "\$4.65," which deducted from the amount brought forward will show in the third place of entry that the total account has been balanced off. By keeping a tabulated statement of the payments on account upon the 85 separate card J the merchant is enabled to tell at a glance the total payments made by the customer and the dates when paid, and therefore is kept informed of the amount of any customer's business during a year or 90 other period of time and is also informed as to his habits and promptness in making payments. In the name-space at the head of 95 this card will be written in legible writing substantially uniform with the headings of the other compartments of the file the customer's name, so that no difficulty will be had in finding any given customer's account in the file. Moreover, this projecting head portion of the card lies over and protects the 100 ends of the sales-slips and when pressed down by the retaining-bar prevents the upper edges of the slips from being roughed up or torn in handling the file. These cards may 105 of course be prepared to receive other items of entry than the above. When a customer's account is closed, his card and slips will be removed, and it is a simple matter to open a new account with a new customer by writing the appropriate index or name words upon 110 this exposed space of a new card and inserting said card or index member in its proper alphabetical or numerical position in the files. These payment-cards will be filed away with the slips or destroyed with them when the account is finally closed or in a long running account may be replaced by fresh cards at any 115 desirable periods. Where these payment-cards are not to be used, or if the merchant prefers it in conjunction with said cards, the 120 compartment flaps or partitions may themselves constitute the index members by having the head portions I formed integrally therewith, as shown in Fig. 6, the name of the 125 customer being written thereon or written on a separate piece of paper or card and pasted or otherwise fastened thereon, as indicated at I in the upper left-hand compartments of the file, the underlying slips being exposed by the 130 cut-away corner at H. It may be desirable

to have these index-heads I hinged to the top of the flaps, as indicated at I', where the Charles Adams' slips appear. This enables the merchant or his bookkeeper to fold back 5 the head portion, so as to expose the upper ends of the underlying slips for the purpose of running them over with the fingers to check up the items upon preceding slips or when carrying forward the footings of one or 10 more slips in writing up the day's accounts. The hinge for this form of the index member may be of cloth or thin leather pasted at the back of the flap and this head portion.

As a still further modification of the device 15 the flaps or partitions B may be provided at their upper ends with spring-clips L, as shown in the lower right-hand compartment of the file and in Fig. 7, said spring-clips being adapted to receive and firmly hold a card 20 upon which is written the appropriate heading or index matter and which then constitutes the index member. This form may be found convenient where accounts are frequently changing. Other modifications may 25 be devised for this index member, and its application is not to be confined to the specific form of file having expandible or hinged flaps, as herein described.

What is claimed as new, and desired to be 30 secured by Letters Patent, is—

1. The combination, with a file comprising a plurality of filing-compartments arranged in series with each compartment in a series projecting beyond the next, of an index member 35 for each compartment projecting beyond the compartment and exposing to view a certain portion only of the uppermost of the contents thereof.

2. The combination, with a file comprising 40 a plurality of filing-compartments arranged in series with each compartment in a series projecting beyond the next, of an index member for each compartment projecting beyond the compartment and cut away at one side

to expose to view a portion of the underlying- 45 contents of the compartment.

3. The combination, with a file comprising a plurality of filing-compartments arranged in series with each compartment in a series projecting beyond the next, of an index member 50 for each compartment comprising a card adapted to be inserted in a compartment, said card when in place projecting beyond the compartment and concealing all but a portion of the underlying contents thereof. 55

4. The combination, with a file of the type described, of an index-card provided with a head portion adapted to project above the top of a compartment when inserted therein, said head portion being partially cut away to 60 expose a portion of the underlying contents of the compartment and the body of the card being ruled off to receive items of entry thereon.

5. The combination, with a file of the type 65 described, of an index member provided with a head portion adapted to project above the top of a compartment, said head portion being partially cut away to expose a portion of the underlying contents of the compartment. 70

6. The combination, with a file comprising a plurality of overlying compartments arranged in series with each compartment in a series projecting beyond the next, of a retaining-bar comprising a hinged bail adapted to 75 be swung over or away from the compartments, one end of said bail being bent into the form of a hook, an eye through which the hook passes at one end of the series of compartments, and a bearing to receive the hook 80 when pushed through the eye to press the bail upon the compartments.

In testimony whereof I have affixed my signature in presence of two witnesses.

ASA E. LANDON.
